GRINDING WHEEL

John F. Fischer, Drexel Hill, Pa., assignor to
 Abrasive Company, Philadelphia, Pa., a corporation of Pennsylvania

Application March 12, 1938, Serial No. 195,632

4 Claims. (Cl. 51—206)

This invention relates to new and useful improvements in grinding wheels of the molded type and more particularly to novel reinforcing means therefor.

5 Grinding wheels of the type mentioned are generally bonded of synthetic resins, rubber, shellac, and like materials and for the most part are employed in high speed work. Usually molded grinding wheels bonded of synthetic resins, rubber, shellac, etc., are reinforced by means of rings which are embedded wholly within the wheel for the purpose of strengthening the same against bursting and preventing the fragments of the wheel from flying asunder when a fracture occurs, and while such rings are effective to some extent, they have certain disadvantages in that the wheels must be fabricated of superimposed layers to permit insertion of the rings and also it is difficult to produce such a grinding wheel 10 which has the high degree of balance desired or required. Furthermore, such rings are wholly embedded within the wheel and therefore afford no visible assurance to an operator that such wheel is reinforced.

25 With the foregoing observations in mind, the principal object of the present invention is to provide a molded grinding wheel wherein novel reinforcing means are provided and constructed and arranged with respect to said wheel so as to afford greater holding power and reinforcement 30 against bursting as the wheel is worn down and the speed of rotation increased.

Another object of the invention is to provide a molded grinding wheel of the character set 35 forth having novel reinforcing means permanently associated therewith and constructed and arranged so as to insure a substantially perfect balanced wheel while permitting unitary or composite fabrication thereof.

40 These and other objects of the invention and the features and details of construction thereof are hereinafter fully set forth and shown in the accompanying drawing, in which:

Figure 1 is a view in perspective of a grinding 45 wheel made according to and embodying the present invention;

Figure 2 is a view in section diametrically through the grinding wheel shown in Figure 1; and

50 Figure 3 is a view similar to Figure 2 showing a modification or modified form of the invention.

Referring now more particularly to the drawing, reference numeral 1 designates a grinding wheel composed of suitable material bonded to

gether by synthetic resins, rubber, shellac or other suitable substance and shaped into annular form by means of a mold in the conventional manner.

5 Embedded and bonded into the grinding wheel 1 during molding thereof are two reinforcing elements 2 and 3 respectively of annular form each having a substantially channel shaped cross section. As shown in Figure 2 of the drawing, the reinforcing elements 2 and 3 each comprise a web portion 4 and flanges 5 and 6 which project substantially at right angles from said web portion 4 at opposite edges thereof. The reinforcing elements 2 and 3 are embedded in opposite faces or sides of the grinding wheel 1 immediately adjacent and surrounding the central opening therein in such manner that the outer surfaces of the web portions 4 and flanges 6 reside respectively flush with or in the plane of the side faces and the wall surface of the central opening of the 20 wheel, while the flanges 5 extend inwardly of the grinding wheel between its inner and outer peripheries substantially parallel to its axis of rotation.

25 From the foregoing description it will be seen that the reinforcing elements 2 and 3 become an integral part of the grinding wheel 1 and although the outer surfaces of the web and flange portions 4 and 6 are exposed to view, the material of the grinding wheel is securely bonded to 30 the inner surfaces of said web and flange portions 4 and 6 and is keyed to the elements 2 and 3 respectively by means of the inwardly extending flange portions 5 thereof which extend parallel to the axis of rotation of the wheel and 35 oppose the action of centrifugal force thereon.

A grinding wheel constructed according to the present invention is preferably supported for rotation between a pair of plates or disks 7 shown in dot and dash lines in Figure 2 of the drawing which grip opposite sides of the grinding wheel at the exposed web portion 4 of the reinforcing elements 2 and 3. The diameter of these supporting disks 7 is slightly less than the outside diameter of the reinforcing elements 2 and 3 so 45 as to not project therebeyond and the disks 7 are further provided with annular flanges 8 arranged to fit snugly within the central opening in the grinding wheel in engagement with the surface of the flanges 6 of the reinforcing elements 2 and 50 3 as shown, thus properly centering the wheel 1 with respect to the disks 7 and the axis of the openings 9 therein through which extends the shaft for driving said wheel.

55 A modification of the invention is shown in

Figure 3 of the drawings and in this particular embodiment thereof the flanges 6a of the reinforcing elements 2a and 3a are appreciably longer and the inner portion of the flange 6a of the element 3a is offset radially as indicated at 10 to receive the overlapping portion of the flange 6a of the element 2a thus providing a wall or lining of uniform bore or diameter for the central opening in the grinding wheel 1. In other respects 10 the reinforcing elements 2a and 3a are identical to the elements 2 and 3 previously described.

In addition to providing maximum reinforcement and more accurate balance in grinding wheels of the present character, the elements 2 15 and 3 or 2a and 3a function to protect the edges of the wheel at the central opening therein during the molding operation and mounting of the wheel for use. These reinforcing elements also serve to reduce wear in the mounting equipment and also 20 provide a metal to metal contact between the grinding wheel and its mounting. Furthermore, the exposed surfaces of the web portions 4 of the reinforcing elements afford solid plane bearing surface at opposite sides of the wheel for the 25 disks 7 and in addition serve as a positive indication to the user of the wheel that suitable reinforcing means are embodied therein.

The invention, of course, is not limited to high speed grinding wheels but may be embodied as 30 desired in molded grinding wheels of any type for any use or work, and while certain specific embodiments of said invention have been illustrated and described herein, it is not intended that the invention shall be limited thereto but that 35 changes and modifications may from time to time be incorporated and embodied therein within the scope of the annexed claims.

I claim:

1. A molded article of the character described 40 comprising an annular body member, and an annular reinforcing element embedded and bonded in each side face of said annular body member immediately adjacent and surrounding the central opening therein, said reinforcing elements 45 each including a web portion disposed flush in a side face of the body member, an edge flange lining at least a portion of the central opening of said body member, and a portion projecting into the body member substantially parallel to its axis of rotation.

2. A molded article of the character described 50 comprising an annular body member, and an annular reinforcing element embedded and bonded in each side face of said body member immediate-

ly adjacent and surrounding the central opening therein, said reinforcing elements each including a web portion disposed flush in a side face of the body member, an edge flange lining at least a portion of the central opening of said body member, and a portion projecting into the body member substantially parallel to its axis of rotation, the edge flanges of the reinforcing elements overlapping one another along the wall of the central opening and one of said flanges being offset radially to receive thelapping portion of the other to provide a lining for the central opening of substantially uniform diameter. 10

3. A molded article of the character described 15 comprising an annular body member, an annular reinforcing element embedded and bonded in each side face of said body member immediately adjacent and surrounding the central opening therein, said reinforcing elements each including a web portion disposed flush in a side face of 20 the body member, an edge flange lining at least a portion of the central opening of said body member, and a portion projecting into the body member substantially parallel to its axis of rotation, and mounting disks secured to opposite side 25 faces of said body member centrally thereof and engaging the web portions of the reinforcing elements, said disks each having a flange thereon fitting snugly within the lining of central opening of the body member. 30

4. A molded article of the character described 35 comprising an annular body member, an annular reinforcing element embedded and bonded in each side face of said body member immediately adjacent and surrounding the central opening 40 therein, said reinforcing elements each including a web portion disposed flush in a side face of the body member, an edge flange lining at least a portion of the central opening of said body member, and a portion projecting into the body member 45 substantially parallel to its axis of rotation, the edge flanges of the reinforcing elements overlapping along the wall of the central opening and one of said flanges being offset radially to receive thelapping portion of the other to provide a lining for the central opening of substantially uniform diameter, and mounting disks secured to opposite side faces of said body member centrally thereof and engaging the web portions of the reinforcing elements, said disks each having 50 a flange thereon fitting snugly within the lining of the central opening of the body member.

JOHN F. FISCHER.
